UNITED STATES PATENT OFFICE.

RICHARD KENNEDY, OF CHICAGO, ILLINOIS.

CARBURETER.

1,019,800.

Specification of Letters Patent. Patented Mar. 12, 1912.

Application filed August 25, 1910. Serial No. 578,903.

To all whom it may concern:

Be it known that I, RICHARD KENNEDY, a citizen of the United States, residing at Chicago, in the county of Cook and State 15 of Illinois, have invented a certain new and useful Improvement in Carbureters, of which the following is a specification.

My invention relates to improvements in carbureters, and is illustrated in one form 10 in the accompanying drawing, which shows a section through my device.

The cylindrical casing A inclosing the annular air passageway A¹ has at one end the enlargement A² which incloses the carbureting chamber A³ in communication with the engine by means of the mixture discharge passage A⁴. The conical partition A⁵ perforated at A⁶ and carrying the screw-threaded hub A⁷, separates the air passage 20 way A¹ from the carbureting chamber A³. The cylinder B which is screw-threaded upon the hub A⁷ is located centrally within the air passage A¹ and contains slidably mounted therein the hollow drum B², 25 mounted upon the hollow piston rod or tube B³ which is in turn slidably mounted within the hub A⁷. The interior of the drum B² communicates at one side with the interior of the tube B³ and is provided at the other 30 with the passageway B⁴ controlled by a valve B⁵ and spring B⁶. The passageway B⁷ in the wall of the tube B³ furnishes communication between said tube and the interior of the cylinder B above the drum B². 35 The spring B⁶ is inclosed within the cylinder B, surrounds the tube B³ and is compressed between the surface of the hub A⁷ and the drum B².

The cylinder B is closed at one end by 40 the fixed drum C which is provided with the passageway C¹ in opposition to the passageway B⁴ in the drum B² and with the passageway C² which may be adjusted by means of the needle valve C³ and which is 45 controlled by the valve C⁴ and spring C⁵. The turn cock C⁶ screw-threaded to the end of the cylinder B communicates with the fuel supply by means of the tube C⁷. The tube B³ which projects upwardly into the 50 chamber A³ carries the hub D from which projects the conical plate D¹ parallel with and adapted to rest upon the partition A⁵ and having the triangular openings D² about its center, and carrying the wire gauze 55 partition D³ through which projects the end of the tube B³.

The enlargement A² is provided at a point farthest removed from the cylinder A with the conical wall E having perforations E¹ therethrough upon which rides the conical collar E² having the perforations E³ therein in opposition to the perforations E¹ and provided with the operating link E⁴.

The cylinder A is provided at its open end with the screw-threaded collar F having the 60 openings F¹ therein in communication with the air passage A¹. The annular collar F² is slidably mounted upon the collar F and is provided with the openings F³ in opposition to the openings F¹ and the operating link F⁴.

It will be evident that while I have shown in my drawing an operative device still many changes might be made in the size, shape and arrangement of parts without departing materially from the spirit of my invention, and I wish, therefore, that my drawing be regarded as in a sense diagrammatic.

The use and operation of my invention are as follows:—When the engine is at standstill and no demand is made upon the carbureter, the conical disk within the carbureting chamber rests upon a corresponding conical wall of said chamber and the drum or piston attached to the tube carried by the conical disk is in its lower position, the fuel having passed upwardly to fill the carbureter above the piston. If now, the engine is started the suction will draw air through the air passage lifting the conical disk. The piston will then rise with the disk and the fuel being compressed by the piston will be squirted out at the top of the piston rod into the carbureting chamber where it will be atomized and carried into the cylinder of the engine. Any fuel which is not carried away by the first stroke will be arrested and caught upon the wire gauze where it will be taken up by the air at the next stroke. The amount of air passing through the carbureter may be adjusted by means of the valve at the opening to the chamber, and this valve which operates to vary the amount of air, also operates to vary the amount of fuel fed to the engine, in view of the fact that the amount of fuel depends upon the length of travel of the conical plate and the piston, and the travel of the piston and plate depends on the amount of air which is drawn through against the plate. The richness of the mixture is ad-

justed by means of the auxiliary air intakes leading to the carbureting chamber above the conical valve plate.

I claim:

- 5 1. A carbureter comprising a cylindrical air passage, a carbureting chamber, separated therefrom by a perforate conical wall, a cylindrical oil chamber concentric with said air passage, a conical valve plate in said carbureting chamber, perforations there-through, a piston in said oil chamber and a piston rod connecting said piston and valve plate, a passage through said piston rod and a check valve in said piston, means for controlling the supply of oil to said chamber, means for controlling said air passage; and an auxiliary adjustable air supply to said carbureting chamber.
- 10 2. A carbureter comprising a cylindrical air passage, a carbureting chamber, separated therefrom by a perforate conical wall, a cylindrical oil chamber concentric with said air passage, a conical valve plate in said carbureting chamber, perforations there-through, a piston in said oil chamber and a piston rod connecting said piston and valve plate, a passage through said piston rod and a check valve in said piston.
- 15 3. A carbureter comprising an air passage, a carbureting chamber, separated therefrom by a perforate wall, an oil chamber within said air passage, a perforate valve plate in said carbureting chamber, a piston in said oil chamber and a hollow piston rod connecting said piston and valve plate, a check valve in said piston.
- 20 4. A carbureter comprising an air passage, a carbureting chamber, separated therefrom by a perforate wall, an oil chamber within said air passage, a perforate valve plate in said carbureting chamber, a piston in said oil chamber and a hollow piston rod connecting said piston and valve plate, a check valve in said piston.
- 25 5. A carbureter comprising a cylindrical air passage, a carbureting chamber, separated therefrom by a perforate conical wall, a cylindrical oil chamber concentric with said air passage, a conical valve plate in said carbureting chamber in opposition to said perforate wall, perforations there-through, a piston in said oil chamber and a piston rod connecting said piston and valve plate, a passage through said piston rod and a check valve in said piston.
- 30 6. A carbureter comprising an air passage, a carbureting chamber, separated therefrom by a perforate wall, an oil chamber within said air passage, a perforate valve plate in said carbureting chamber in opposition to said perforate wall, a piston in said oil chamber and a hollow piston rod connecting said piston and valve plate, a check valve in said piston.
- 35 7. A carbureter comprising a carbureting chamber, a perforate disk slidably mounted upon the walls thereof, a tubular piston rod carried by said disk and pumping means carried by said piston rod, means for closing and unclosing the perforations in said disk.
- 40 8. A carbureter comprising a carbureting chamber, a perforate disk slidably mounted upon the walls thereof, a tubular piston rod carried by said disk and pumping means carried by said piston rod, means for closing and unclosing the perforations in said disk, said means comprising a fixed wall in opposition to said disk.
